CLAIM

The ornamental design for an electronic device holder, as shown and described.

DESCRIPTION

FIG. 1 is an upper perspective view of an electronic device holder showing the new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines in the drawings are included for the purpose of illustrating portions of the electronic device holder that form no part of the claimed design.

1 Claim, 5 Drawing Sheets(56)
